UNITED STATES PATENT OFFICE.

CHARLES L. HART, OF BROOKLYN, NEW YORK.

CAN SEAMING AND CRIMPING MACHINE.

SPECIFICATION forming part of Letters Patent No. 324,318, dated August 11, 1885.

Application filed April 8, 1885. (No model.)

To all whom it may concern:

Be it known that I, CHARLES L. HART, of Brooklyn, Kings county, New York, have invented a new and useful Improvement in 5 Can Seaming and Crimping Machines, of which the following is a specification.

My improvement applies more especially to that class of can crimping or seaming machines such as shown in the Patents Nos. 10 245,392 and 247,816, of August 9 and October 4, 1881; and the object of my invention is to construct a machine in which the operations of seaming the bottom of a sheet-metal 15 article and curling or turning over the metal at the mouth thereof, termed "wire-edging," may be carried on simultaneously; and to this end my invention consists in combining, with the face-plate, block, or table of a seaming-machine a means or mechanism for curling 20 or turning over the metal at the mouth of such article, as hereinafter set forth.

In the accompanying drawings, forming part of this specification, Figure 1 represents a front elevation of a double-seaming machine 25 embodying my invention. Fig. 2 is a cross-section thereof on line *x x* of Fig. 1. Figs. 3 and 4 represent an article in the different stages of manufacture, showing the operation 30 of the seaming and curling or turning mechanisms on the said article. Fig. 5 shows the application of my invention to a horizontal single seaming-machine.

Referring to the drawings, A represents the article-supporting table or face-plate, rendered 35 vertically adjustable by means of the stationary rack B, with which the pinion C, mounted in the table-supporting bracket D, engages, said pinion being operated by a hand-wheel, E, as shown. The said table is raised or lowered 40 in its bracket by means of the foot-lever E', pivoted to the base and connected to the lever F, mounted in the said bracket, the latter acting on the stem-shaft or projection G of said table.

45 The power for driving the machine is applied to pulley H on shaft I, which carries the chuck or disk K for engaging the bottom of the can or article to be completed. The bifurcated lever L, carrying the two grooved 50 rolls M and N, for successively turning over and pressing down or flattening the double

seam, is pivoted to the adjustable support O, as indicated in Figs. 1 and 2.

The parts so far referred to are old, and the operation of seaming a can or other article by 55 the mechanism shown is well-known and need not be herein specifically described.

As a means for curling or turning over the metal at the mouth of the can or other article, so as to give it the appearance of being wired, 60 I mount in bearings on the table A a series of suitably-grooved rollers, 2, on which the article is placed and supported, and these rollers are so arranged—*i. e.*, at such a distance from the center of the table—that the said 65 article will lie close to the inner flanges of said rollers. To adapt this means to cans of different diameters, I mount said rollers in radially-adjustable supports or bearing-blocks 3, arranged to slide in undercut or equivalent 70 grooves 4, formed in the table and held in place by means of headed screws 5 and clamping-nuts 6, or by any other suitable means. If desired, the journals of said rollers may be supported in spring-pressed bearings arranged 75 in said bearing-blocks. (See Fig. 5.)

The operation of the machine is as follows: The mouth of the can or article is placed on the grooved rollers and the table elevated to press the bottom of the can against the chuck 80 or disk of the revolving shaft I. Power is now applied to pulley H to revolve said shaft and with it the can held by its chuck. The table, however, will not revolve, as it is prevented from turning by a key or feather, d, 85 on the bracket D, and hence as the mouth of the can rests on the grooved rollers 2, and is revolved over the same by the rotation of the chuck K, the rollers are also caused to revolve against the edge of the can, and thus operate 90 on or travel over all points of the mouth edge of the can. Any upward movement now of the table caused by depressing the foot-lever will exercise a pressure on the can and cause the rolls to act on the metal at the mouth 95 thereof, to curl or turn it over outwardly onto itself, as indicated in Fig. 3. This pressure upward by the table is continued, the said table being gradually elevated more and more as the metal at the mouth of the can is curled 100 over until the metal has returned upon itself and presents in cross-section the form illus-

trated in Fig. 4. While this operation at the mouth of the can is taking place the double seam is formed at the bottom of the can by the operation of the rolls M and N through manipulation of the lever L in the usual way, the roll M being first pressed up to the seam, as seen in Fig. 3, to curve in the metal, after which the roll N is pressed up to flatten down and complete the seam, as seen in Fig. 4.

10 In Fig. 5, which represents a horizontal single-seaming apparatus, the head or block A, which is also prevented from turning, is formed with dovetailed grooves 7 on its periphery, in which the blocks 3 slide, the latter being provided with journals 9, on which the grooved curling-rolls 2 are mounted. The said roll-carrying blocks are pressed forward by springs 11, so as to exert a yielding pressure on the article, to prevent the latter from 15 buckling, which might occur when thin sheet metal is employed, and to insure the even overturning of the edge. The can or other article is held between the chuck H of the mandrel and the curling-rolls of head A, the 20 arrows showing the direction of rotation of the mandrel and the direction of movement of head R, and the operation and result are 25 substantially the same as in the case of Fig. 1. The seam is flattened by the roll, carried by lever T in the ordinary manner. It will therefore be seen that by this improvement in seaming-machines I am enabled to produce the overturned curled or wire edge on the mouth of the can simultaneously with 30 the formation of the bottom seam, and without requiring any appreciable additional thought or attention on the part of the operator from what is required to form the usual seam, and this result is accomplished by a very slight 35 and inexpensive addition to the regular seaming-machine, which in no way interferes with its seaming functions, thus combining a seaming and a wire-edge machine in one, and performing both actions at the same time, 40 which greatly conduces to economy and ease of manipulation.

What I claim as my invention, and desire to secure by Letters Patent, is—

1. The combination, with the rotary chuck of a can-seaming machine, of a non-rotating 50 face-plate, block, or table, and a series of rolls mounted on said face-plate, block, or table, substantially as described.

2. The combination, with the rotary chuck of a can-seaming machine, of a non-rotating face-plate, block, or table, and a series of grooved 55 rolls mounted on said face-plate, block, or table, substantially as described.

3. The combination, with the non-rotating face-plate, block, or table of a can-seaming 60 machine, of a series of rolls journaled in adjustable bearing blocks or supports mounted on said face-plate, substantially as described.

4. The combination, with the face-plate, block, or table of a can-seaming machine, of a 65 series of rolls carried by movable bearings mounted on said face-plate, substantially as described.

5. The combination, with the face-plate, block, or table provided with a series of radial under cut grooves, of bearing-blocks arranged to slide in said grooves, curling-rolls mounted in said blocks, and clamping means for holding said blocks stationary, substantially as described. 70

6. The combination, in a can-seaming machine, of the mandrel and its chuck, with mechanism for seaming a can, and a face-plate or block provided with a series of curling-rolls for curling or turning over the metal at 75 the mouth thereof, substantially as described.

7. The combination, in a can-seaming machine, with the rotary chuck for revolving the can, and mechanism for seaming the bottom joints thereof, of a face-plate or table provided with a series of rolls on which the mouth-edge of the can rests, and means for pressing the rolls against the edge of the can, whereby the formation of the bottom seam and the curling over or wire-edging of the can may be performed simultaneously, substantially as herein set forth. 80 85 90
